UNITED STATES PATENT OFFICE.

PATRICK BROWNLEY, OF ST. JOHN, NEW BRUNSWICK, CANADA.

LUBRICATOR.

SPECIFICATION forming part of Letters Patent No. 374,729, dated December 13, 1887.

Application filed April 26, 1887. Serial No. 236,199. (No model.)

To all whom it may concern:

Be it known that I, PATRICK BROWNLEY, a subject of the Queen of Great Britain and Ireland, residing at St. John, in the Province of New Brunswick and Dominion of Canada, have invented new and useful Improvements in Lubricators, of which the following is a full, clear, and exact description.

This invention relates to lubricators of a form adapted for use in connection with the steam-chests of locomotive, hoisting, and other steam-engines, the object of the invention being to provide a lubricator which shall not depend upon suction or the formation of a vacuum for the proper operation of the lubricator-valves; and to this end the invention consists of a lubricator wherein the feeding-chamber is provided with induction and eduction valves, the eduction-valve being formed with a stem which bears against the under side of the induction-valve and raises said valve from its seat when the said eduction-valve is subjected to the pressure of the steam delivered to the steam-chest, all as will be hereinafter more fully described, and specifically pointed out in the claims.

Reference is to be had to the accompanying drawings, forming a part of this specification, in which similar figures of reference indicate corresponding parts in all the views.

Figure 1 is a central sectional elevation of my improved form of lubricator, the feed-chamber valves being represented in the position they assume when the eduction-valve is seated. Fig. 2 is a detail view of the feed-chamber and its connections, the parts being represented as they appear when the induction-valve is seated and the eduction-valve is moved from its seat; and Fig. 3 is a sectional plan view, the view being taken on a line corresponding with the line xx of Fig. 1.

In the drawings above referred to, 10 represents the lower casting of my improved form of lubricator, said casting being formed with a central bore, 11, a steam-passage, 12, and a valve-chamber, 13, the chamber 13 and the bore 11 being in communication through the medium of a passage, 14, while the passage 12 leads directly to the bore 11. The walls of the chamber 13 are threaded, in order that they may be engaged by an external thread that is

formed upon the lower end of a feed-chamber, 15, said feed-chamber being in turn formed with a flange, 16, that is adapted to receive the bite of a wrench, being square, hexagonal, 55 or of any other proper form.

The feeding chamber 15 is provided with an induction valve, 17, that is seated in an aperture formed in the upper wall of the chamber, the stem 18 of this valve 17 projecting upward 60 through a guiding-socket that is formed in a spider, 19, said spider being connected to the feeding-chamber, as indicated, and the valve being normally held against its seat by a spring, 20.

In the lower wall of the case forming the feeding-chamber I arrange an eduction-valve, 21, that is preferably formed with a concave lower face, as illustrated. Recesses 2 are formed in the edge of the valve 21, to provide 7c for the passage of the lubricating material. The valve 21 is provided with a stem, 22, which extends upward, so as to bear against the under side of the valve 17 at times when the valve 21 is forced to its seat.

The casting 10 has an internally-threaded flange, 24, that is engaged by an external thread formed on the outer side of a cylinder, 25, said cylinder resting upon a packing ring or washer, 26. The upper end of this cylinder 80 25 is closed by a cap, 27, which cap is formed with a centrally-apertured boss or projection, 28, this boss being internally threaded to receive a closing-plug, 29, which is centrally bored, as shown.

The space within the cylinder 25 constitutes the oil-supply reservoir or chamber 30, and through this chamber I pass a tube, 31, one end of said tube being threaded to engage with a thread formed in the walls of the passage 90 12, while the other end of the tube is connected to a short tube, 32, by means of a right and left hand coupling, 33; or the coupling 33 might be of any other form desired. The tube 32 communicates with an elbow, 34, which engages 95 with a proper aperture formed in the casting 10, as does also the tube 32, and the elbow 34 is in turn connected with a regulating-cock, 35. A vent-pipe, 36, leads from the chamber 15 upward through the chamber 30 and out 100 through the plug 29, as shown. A petcock, 37, is arranged, as indicated, so that the con-

tents of the chamber 30 may be drawn off when desired.

The lubricator described is connected to a steam-chest through the medium of its threaded projection 38, and, being so connected, the steam entering said steam-chest will be free to enter the bore 11 to find a partial exit through the passage 12 and tubes 31, 32, and 34, the amount of steam passing through said tubes being regulated by the cock 35, the idea of so conducting the steam through the chamber 30 being to maintain the lubricant contained within said chamber in a liquid condition. The steam, entering the bore 11, also finds its way to the valve chamber 13, and the pressure exerted by the steam will seat the valve 21, thus unseating the valve 17, and as the valve 17 is so unseated the feeding-chamber 15 will be filled from the chamber 30, as said chamber is vented through the tube 36; but when the steam is cut off from the steam-chest the pressure of the atmosphere exerted through the tube 36 will force the valve 21 from its seat and the contents of the chamber 15 will be delivered to the steam-chest, the valve 17 at this time being forced to its seat by the spring 20.

From the above description of the operation of my improved form of lubricator it will be seen that when the throttle communicating with the steam-chest of the engine is open the valve 21 will always be seated, but that the contents of the chamber 15 will be delivered to the steam-chest immediately upon the closing of the throttle, the supply of lubricating material delivered to the steam-chest being regulated by varying the size of the chamber 15.

Having thus fully described my invention,

I claim as new and desire to secure by Letter Patent—

1. The combination, with the oil-reservoir of the feeding-chamber in the bottom thereof a downwardly-opening valve in the bottom of the feeding-chamber, a separate and independent downwardly-closing valve in the top of the chamber, to be raised by the upward movement of the valve below it, and a vent-tube leading into the feeding-chamber, substantially as set forth.

2. The combination, with the oil-reservoir having central openings, 11, 14, and 13, in its bottom, of the chamber 15, threaded at its lower end to engage the threaded walls of opening 13, and provided with valve-seats in its top and bottom, the downwardly-opening gravity-valve 21, having recesses 2, and a stem, 22, extending into said chamber, the separate and independent upper valve, 17, having a stem, the spider 19, having a guiding-socket for said stem, and the spring 20 on said stem, substantially as set forth.

3. In a lubricator, the combination, with a bottom casting having a central bore and a valve-chamber, of a casing constituting a feeding-chamber, valves arranged in connection with said chamber, a vent-pipe leading to said chamber, a storage-chamber within which the feeding-chamber is arranged, a steam-pipe arranged in the storage-chamber, and a means for regulating the supply of steam passing through said pipe, substantially as described.

PATRICK BROWNLEY.
